UNITED STATES PATENT OFFICE.

ABELINO FERNANDEZ ROCES, OF MANZANILLO, CUBA.

HOISTING APPARATUS.

1,391,411.

Specification of Letters Patent. Patented Sept. 20, 1921.

Application filed October 30, 1919. Serial No. 334,547.

To all whom it may concern:

Be it known that I, AVELINO FERNANDEZ ROCES, a subject of the King of Spain, of No. 18 Loinaz del Castillo St., Manzanillo, 5 Cuba, have invented certain new and useful Improvements in Hoisting Apparatus, of which the following is a specification.

The invention relates to a hoisting apparatus, and particularly to an apparatus 10 for loading and unloading vehicles with bulky goods or articles.

It is an object of the invention to provide a hoisting apparatus which may be conveniently installed and removed with respect to a vehicle or a number of vehicles 15 so that the goods of one vehicle may be transferred onto another or a vehicle may be loaded or unloaded.

A further object of the invention consists 20 therein that a carrying frame adapted to receive the goods is provided on the hoisting apparatus such that by a simple manipulation of a control device the frame together with the goods is raised, thence shifted laterally, and thence lowered so that the 25 transferring of a load from one place to another or from one vehicle to another may be conveniently and efficiently effected.

A further object of the invention aims at 30 the provision of means for securing the goods in raised position to prevent their return to initial position under their weight.

With these and other objects in view, which will become apparent as the description 35 proceeds, a preferred embodiment of the invention is illustrated in the accompanying drawing, described in the specification, and particularly pointed out in the claims forming a part thereof.

40 In said drawings, Figure 1 is a side view of the hoisting apparatus constructed in accordance with the invention;

Fig. 2 is a view of the front tripod constituting a part of the structure;

45 Fig. 3 is a view of the rear tripod;

Fig. 4 is a side view of the pulley wheels from which the carrying frame for the goods is suspended; and,

50 Fig. 5 is a front view of the parts shown in Fig. 4.

Referring to the several views of the drawing 1 designates the front member of the structure for hoisting goods, which member comprises an I-beam laterally secured by 55 braces 2. The latter intermediate their ends are inter-connected with the I-beam 1 by a

horizontal bar 3. Coacting with the front member 1 is a rear member 4 somewhat higher than the fore front member and constructed in a similar manner. The member 60 4 also comprises an I-beam which is supported from the ground by lateral braces 5 which together with the central member 4 constitute a tripod. A transverse bar 6 connects the I-beam 4 with intermediate portions of 65 the braces 5. As indicated in Fig. 1, the members 1 and 4 are secured to the ground in inclined upwardly converging position and the upper ends are interconnected by a longitudinal I-beam 9 which is secured to the 70 appertaining members in any approved or desired manner, preferably by riveting, as shown at 7 and 8. The structure is preferably so arranged that the inclination for the beam 9 is 22° as, from practical experience, it has been established that the apparatus operates most satisfactorily if the upper flange 10 of the I-beam 9 forms the angle 75 of 22° with a horizontal plane. The load-carrying frame comprises bars 11 and 12 arranged respectively at each side of the I-beam 9 and depend from a horizontal shaft 13, protruding from a pulley wheel 14, which is equipped with end flanges 15 and 16, and travels on the upper flange 10 of the I-beam 80 9. To the inner side of the bars 11 and 12 horizontal bars 17 and 18 are secured which at the extremities receive shafts 19 and 20 of pulley wheels 21 and 22. On the flange 10 of the upper beam abutments 23 and 24 are 85 arranged to limit the range of movement of the pulley wheel 14 and therewith of the load sustained thereby. Brackets 25 and 26 are secured to the beam 9 and the member 4, respectively, and constitute a journal for 90 shafts 27 and 28, respectively, carrying pulley wheels 29, 30 and 31, 32, as clearly appears in Fig. 1. The load-engaging and carrying frame 33 is secured to a running block 34 equipped with a pulley 35, around 95 which a cable is trained. The winding drum for the cable is supported in bearings 38 secured to the ground. A shaft 39 carrying drums 40 and 41 is journaled in the bearings. The larger drum 40 winds up or pays out 100 the cable 42 whereby the hoisting apparatus is actuated. A brake 43 is arranged on the shaft 39 and provided with a control lever 44 whereby the rotation of the drum 40 is controlled. The load-controlling cable 45 105 is wound on the drum 41 in a direction opposite to that of cable 42; is then trained

around the pulley wheels 30 and 32; is then led over the pulley 22 to encompass the pulley 35, thence is carried around the pulley 21 and is secured at 37 to the running block 34. In order to secure the load at the highest position, a counter-weight 46 is secured to a cable 47 which is trained around the pulleys 29 and 31 and is secured at its end at 48 to the bars 11 and 12. The counter-weight 46 has depending therefrom a hook 49 adapted to engage the staple 50 secured to the ground. When the hook 49 engages the staple 50 the load will occupy the highest position such that the pulley 14 bears against the abutment 24 on the inclined member 9.

In the operation of the device when it is desired to transfer the load from a cart 51 to a car 53 the brake lever 44 is manipulated to permit rotation of the winding drum and 20 unwinding of the cable whereby the running block 34 and the frame 33 will descend until the chains 54 can be arranged around the load. Subsequently, the cable 42 is wound on the drum, either manually or by deriving 25 motion from a suitable source of power and during the rotation of the winding drum 40, the drum 41 moves in concert whereby the load will be raised until the pulley wheel 35 meets the wheels 21 and 22. The ascent 30 of the load will then stop and the continued revolution of the drums 40 and 41 will cause movement of the bars 11 and 12 so that the load travels laterally on the longitudinal member 9 and reaches the highest position. 35 This lateral motion comes to a stop when the pulley wheel 14 engages the abutment 24, in which position then the hook 49 of the counterweight 46 will engage the staple 50, and thus prevent lowering of the load. After 40 the load has been shifted to its uppermost position the brake is again released whereby the load may descend until it is placed in the car 53.

The drawing discloses a preferred embodiment of the invention without, however, disclosing all of the possible modifications which may be adopted within the spirit of the invention. I, however, do not limit myself to the constructional features, as shown, 45 but desire to avail myself of any changes, 50

alterations and modifications constituting departures within the scope of the invention, as defined by the appended claims.

I claim:

1. A hoisting apparatus of the character 55 specified, including a frame comprising a slanting beam, oblique members of unequal height supporting the ends of said beam from the ground, a pulley secured to the lower end of said beam, a second pulley secured to the upper end of the higher oblique member, a carriage movable on said beam and provided with a pair of pulleys, a cable trained around said pair of pulleys to form a loop, a running block arranged in said loop 60 and having one end of said cable secured thereto, a winding drum from which said cable originates, said cable being trained around said second pulley and around said 65 first named pulley to provide thereby successively raising or lowering of the running block and lateral movement of said carriage on said beam upon proper rotation of said drum.

2. A hoisting apparatus of the character 70 specified, including a frame comprising a slanting beam, oblique members of unequal height supporting the ends of said beam from the ground, a pulley secured to the lower end of said beam, a second pulley secured to the upper end of the higher oblique member, a carriage movable on said beam and provided with a pair of pulleys, a cable trained around said pair of pulleys to form a loop, a running block arranged in said 75 loop and having one end of said cable secured thereto, a winding drum from which said cable originates, said cable being trained around said second pulley and around said first named pulley to provide thereby successively raising or lowering of the running block and lateral movement of said carriage on said beam, and a weighted hook suspended 80 from the carriage and adapted to be placed in engagement with a fixed staple 85 upon said carriage reaching the highest position.

In witness whereof I affix my signature.

VELINO FERNÁNDEZ ROCES.
